UNITED STATES PATENT OFFICE.

GUSTAV HUGUENIN, OF CHAM, SWITZERLAND, ASSIGNOR TO NESTLE AND ANGLO-SWISS CONDENSED MILK COMPANY, OF CHAM, SWITZERLAND, A CORPORATION OF SWITZERLAND.

BOX OR CONTAINER FOR USE IN THE CONVEYANCE OR TRANSPORT OF GOODS OR MERCHANDISE.

Application filed October 19, 1922. Serial No. 595,691.

To all whom it may concern:

Be it known that I, GUSTAV HUGUENIN, a citizen of the Republic of Switzerland, residing at Cham, Switzerland, have invented 5 certain new and useful Improvements Relating to Boxes or Containers for Use in the Conveyance or Transport of Goods or Merchandise, of which the following is a full, clear, and exact description.

10 This invention has reference to boxes or containers for use in the conveyance or transport of goods or merchandise particularly those boxes or containers that are constructed of wood and bound with metal strips or bands to afford strength and security thereto and relates to an improved method of securing metal fittings, binding bands or strips whereby the contents of such boxes or containers are rendered practically 15 immune from tampering or being surreptitiously dealt with.

20 The invention therefore consists in securing the metal fittings by means of pins, nails, screws or the like, which are driven in and 25 through the said fitting from the outside and welding the heads or outer ends thereof so as to furnish a wholly one or integral structure the union presenting a flat smooth and uninterrupted surface.

25 Ordinary nails may serve in carrying out the above described method of securing the cases and give fairly satisfactory results. It has been found in practice however that the metal composing the head is insufficient 35 when fusion takes place to yield the degree of security aimed at. A nail or the like has therefore been devised which is adapted to effect the desired results and in the preferred form comprises a head of large or thick construction and of conical formation with a tapering shank depending therefrom. Between the head and the shank there may be provided an annular part or flange to facilitate distribution of the nails when employing a nailing machine.

The welding is effected preferably electrically and the meeting ends of the binding may if desired be welded together. When secured in the manner herein described any 50 attempt may be immediately detected and the re-instatement of the fittings in their original welded condition rendered impossible of accomplishment. Robbery or pilfer-

ing of the contents is hereby frustrated, the concrete and integral condition of the box 55 and metal fittings, binding bands or strips ensuring the safe and undisturbed passage of the goods or merchandise.

In order that the invention may be clearly understood same will now be more fully described with reference to the accompanying drawings in which:—

Figure 1 is a view in perspective of a portion of a packing case, box or container such as hereinbefore referred to having a binding of hoop iron applied and secured in accordance with the method of the said invention.

Figure 2 shews diagrammatically the binding of a case secured by the method 70 herein described.

Figures 3, 4 and 5 are side views of edge fittings secured according to the invention.

Figure 6 illustrates a further alternative form of iron or metal fitting adapted for 75 being secured according to the improved method.

Figure 7 is an enlarged view of a nail or the like designed for use in welding according to the invention.

Referring to Figure 1 an endless band of hoop iron 1 is applied about the case, box or container and fastened thereto by means of pins or nails 2. This hoop iron 1 may advantageously be applied to the box or container where the parts of the latter are connected together by nails 3 so that the binding covers the heads of the said nails 3 as is usually the case. The said binding may be applied to the box as a continuous band whereof the meeting ends of the strip forming the same are welded together or the strip may be applied about the box and the ends thereof welded during the process of welding the nail heads thereto whereby the said 90 binding is secured to the box.

It has frequently been observed that boxes or containers secured simply by a binding applied over the fixing nails 3 pertaining to the parts of the box as just described 100 have been opened by withdrawing the nails such as indicated at 2 and 3 and removing the binding strip 1 and the contents taken out or otherwise disturbed or tampered with, the case or box being thereupon closed or restored to its original condi-

tion, the theft or tampering that has occurred during the transit being undetected until the arrival of the box or container at the place of destination.

- 5 The present invention is designed to obviate or prevent such untoward occurrences and to this end the outer end or head of each pin or nail 2 is formed approximately as illustrated in the enlarged detail 10 view Figure 7 the head *a* being of large or thick construction and of conical form having an annular part or flange *b* at the base of the cone for the purpose hereinbefore mentioned and a tapering shank *a*¹ depending from the said annular flange. The latter may however be dispensed with and the said shank be arranged directly depending from the base of the conical head *a*. The said head the nail or the like having been driven in and through the binding into the material composing the box or case is welded preferably electrically to the hoop iron binding or strip 1 so as to consolidate the same or render the pin or nail 15 head or end wholly one or integral with the said binding, which after its union with the nails presents a flat and smooth surface without projection of any kind whatever whereby attempts could be made to loosen 20 the nails or which would offer any obstacle or resistance during the handling of the case or box. When so constituted and secured the pins or nails 2 cannot be separated from the binding or strip 1 and rejoined to it 25 30 without involving damage to the parts. In arranging the fixing means it is preferable and desirable that the distance *d* (Figure 1) between two nails 2 or 3 or a nail 2 and a nail 3 be such that no part of the packed 35 40 goods can be extracted by cutting a piece from the wood constituting the case or box between the nails which could be replaced without leaving traces, particularly as top, bottoms and sides of cases are commonly 45 made of several boards fitted together by tongues and grooves or slots.
- In the example illustrated in Figure 1 it will be observed that the pins or nails 2 are arranged on each of the sides of the case, 50 box or container. It is however sufficient if the said pins or nails be arranged on two opposite sides only as shown diagrammatically in Figure 2.
- It is preferable and desirable to arrange 55 the pins or nails at the corners of the cases or boxes near the contact edges of the two sides thereof whereby the distance *c* (Figure 2) between the nail and the said contact edges is so small that the binding or 60 strip cannot be bent away from the case or box and latter be pressed back again into its original position thus rendering the unobtrusive removal of the fittings impossible.
- 65 Referring to Figure 3 the box is shown

as provided with edge-fittings, the said fittings being fixed by means of pins or nails 2 which meet or pass each other at an angle and whereof the heads are electrically welded to the said corner fitting.

Angle-irons are arranged as fittings in Figures 4 and 5 and as shown fixed by means of pins or nails 2 driven at right angles to each other the heads of the several pins or nails being welded to the metal of the angle iron.

In the example, illustrated, in Figure 6, a clamp-like fitting 6 is provided, a spike being formed at right angles thereto adapted to be driven into the side of the case, box or container. The nail 2 is then driven into the adjacent side so as to traverse the said spike and the head electrically welded to the clamp-like fitting as will be readily understood.

From the foregoing description it will be readily apparent that by the use of a packing case, box or container produced and secured according to the improved method the contents are practically immune from tampering, pilfering or robbery as any attempt to gain access to the contents is completely frustrated by the means of detection afforded by the fracture of the metal fitting, binding or strip which is readily visible and which is necessary in order to open the box or container. The unimpaired condition of the package is moreover rendered clearly and readily observable.

I claim:—

1. In securing metal fittings, binding bands or strips to boxes or containers for the conveyance or transport of goods or merchandise, the herein described method which consists in welding together the said fittings and the heads of their securing pins or nails which comprise thick and spreadable coniform heads and depending tapering shanks whereby an integral union is effected and a flat, smooth and uninterrupted surface presented with no projection of any kind.
2. In securing metal fittings to boxes or containers for the conveyance of goods or merchandise, the herein described method which consists in providing the securing pins with heads of ample proportions, inserting the shanks of said pins in and through a fitting consisting of an endless binding band and welding the adjacent parts of said pin heads and band so as to integrally unite the same.
3. In securing metal fittings to boxes or containers for the conveyance of goods or merchandise, the herein described method which consists in providing nails comprising a head of large proportions and of conical formation with a tapering shank depending from the base of the said head, driving the said nails through the metal fit-

ting and into the material of the box or container and welding the enlarged and conical nail heads to the adjacent parts of said metal fitting so as to integrally unite the 5 same.

4. In securing metal fittings to boxes or containers for the conveyance of goods or merchandise, the herein described method which consists in securing the parts of the 10 box by ordinary nails, fitting about the sides of the box and over the said ordinary nails a metal band, driving through the said metal band and into the material of the box nails, comprising a head of large construction 15 and conical formation with a tapering shank depending from the base of said head, in alternating sequence, with said ordinary nails so as to present a large headed nail near each angle of the box and then welding 20 the enlarged and conical heads to the adjacent parts of said metal band to integrally unite the same.

5. In securing metal fittings to boxes or

containers for the conveyance of goods or merchandise, the herein described method 25 which consists in securing the parts of the box by ordinary nails, fitting about the sides of the box and over the said ordinary nails a metal band, driving through the metal band and into the material of the box in alternating sequence with the said ordinary nails and on opposite sides of the box nails comprising a head of large proportions and conical formation with a tapering shank depending from the base of said head so as to 30 present a nail head near each angle of the box having a mass of metal sufficient for welding purposes and then welding the said heads to the adjacent parts of the metal band to integrally unite the same. 35

In witness whereof I have hereunto subscribed my signature 30th September, 1922.

GUSTAV HUGUENIN.
